UNITED STATES PATENT OFFICE.

CHARLES FORREST McBEE, OF ATHENS, OHIO.

BOOKBINDING.

1,134,142.

Specification of Letters Patent.

Patented Apr. 6, 1915.

Application filed October 18, 1911. Serial No. 655,411.

To all whom it may concern:

Be it known that I, CHARLES F. McBEE, a citizen of the United States, residing in Athens, county of Athens and State of Ohio, have invented a new and useful Improvement in Bookbindings, of which the following is a specification.

My invention relates to an improvement in loose leaf binders wherein a temporary binder leaf is initially employed in conjunction with a permanent binder device, the temporary binder leaf being provided with means for locking or clamping to the permanent binder devices and being expansible relative thereto; the temporary binder leaf also being provided with means for receiving a portion of a collocation of loose sheets for temporary separation of said sheets at a desired point; and the permanent binder being adapted for use independently of the temporary binder leaf when a collocation of loose sheets therein is complete and ready for permanent binding.

The object of this invention is to provide an improved construction for loose leaf binders.

A further object of this invention is to provide improved temporary locking means for a loose leaf binder.

A further object of this invention is to provide improved permanent locking means for a loose leaf binder.

A further object of this invention is to provide improved means for separating and separately maintaining the parts of a collocation of loose sheets in a binder during the operation of abstracting a single sheet or a plurality of successive sheets for temporary use or treatment extraneous to the binder.

My invention consists in the construction, arrangement and combination of elements hereinafter set forth, pointed out in my claims and illustrated by the accompanying drawing, in which—

Figure I is a plan of the complete device in extended position. Fig. II is a transverse vertical section on the line II—II of Fig. I, dotted lines indicating closed position of a permanent binder leaf. Fig. III is a detail vertical section on the line III—III of Fig. I, on an enlarged scale, dotted lines indicating a clamping device in inoperative position. Fig. IV is a detail vertical section on the line IV—IV of Fig. I, on an enlarged scale. Fig. V is an end elevation showing the temporary binder leaf in an auxiliary

position assumed at times. Fig. VI is an end elevation showing the permanent binder containing a collocation of loose sheets, dotted lines indicating closed position of the binder.

In the construction of the device as shown the numerals 10, 11 designate permanent binder leaves, which leaves are flexibly connected at their rear margins to a back 12. The cover thus formed may be of any desired size and may be constructed in any suitable manner, as of board covered with cloth or canvas and suitably finished. Stubs 13, 14 are flexibly connected to the inner margins of the leaves 10, 11 respectively, and said stubs preferably are of slightly less length and materially less width than said leaves. Tubular posts 15, 16 are fixed in any desired manner to and rise from the right hand stub 14 adjacent the ends thereof, and said posts are of approximately the same length as the width of the back portion 12. Eyelets 17, 18 are formed in the left hand stub 13 and are adapted to register with the posts 15, 16 at times. A temporary binder leaf 19 is provided and is formed with a stub 19^a flexibly attached thereto at its left hand margin, the combined widths of the binder leaf and its stub preferably coinciding with the width of either leaf 10, 11. The stub of the temporary binder leaf 19 is formed with holes 19^b adjacent its ends adapted to fit loosely on the posts 15, 16. Latching or clamping devices are mounted on the stub 19^a and are adapted to engage the posts 15, 16 at times and lock the temporary binder leaf to said posts. Each clamp or latch (particularly see Fig. III) has a base plate or bar 20 secured to the stub 19^a by rivets 21. The base plate 20 is formed with a hole 20^a registering with the hole 19^b in the stub 19^a and adapted to receive loosely a post 15 or 16. A spring 22 is fixed at one end on one or more of the rivets 21, extends longitudinally above the base plate 20, and is formed with a longitudinal slot 23 adjacent its free end adapted to receive a post 15 or 16. A cam latch 24 is pivotally connected to one end portion of the base plate 20 by means of a pin 25 mounted transversely of an end-opening notch 26 in said plate. The cam latch preferably is formed with a plane back margin adapted to lie flat on the upper surface of the stub 19^a; and is formed with an irregularly curved front margin adapted to engage, raise and sustain the free end of the

spring 22, which is curved upward slightly for sliding contact with said cam. The location of the spring 22 and the slot 23 therein is such that when the spring is in elevated 5 position (dotted lines Fig. III) said slot will loosely engage and slide on a post 15 or 16 so that the temporary binder leaf may be removed or adjusted relative to the posts; but when the spring 22 is released, by down- 10 ward movement of the cam 24, one margin of the slot 23 frictionally engages the post 15 or 16 and holds said temporary binder leaf in any position in which it may be placed altitudinally of the posts.

15 Studs 27, 28 are swiveled in and rise from the upper surface of the temporary binder leaf 19 adjacent its right hand margin and spaced apart to correspond to the spacing of the posts 15, 16. The studs 27, 28 are forked 20 at their upper ends and embrace end portions of arched rods 29, 30, which rods are pivoted to said studs by pins 31. The arched rods 28, 30 may be folded flat against the upper surface of the temporary binder leaf 19 25 and secured in such position by means of spring slips 32, 33 fixed to the upper surface of said leaf. The arched rods 29, 30 are formed with spindles 29^a, 30^a of reduced diameter on their free ends adapted to be received within the open upper ends of the posts 15, 16.

In practical use loose sheets such as 34 are properly apertured and are placed on the posts 15, 16 and then the temporary binder 35 leaf 19 is mounted on said posts above the sheets as shown in Fig. II and is secured by releasing the cam latches 24. The margins of the sheets 34 are thus firmly held between the studs 14 and 19^a and are securely bound. 40 The quantity of sheets 34 may be added to from time to time as desired, limited only by the effective length of the posts 15, 16.

At times it is desirable to remove a single sheet or a quantity of successive sheets from the binder, and it is also desirable to provide means for maintaining the succession and vertical alinement of other sheets which may be mounted above the sheets to be removed. It is for this purpose I have provided the arched rods 29, 30. When it is desired to remove one or more sheets from the interior of the pile 34 the temporary binder leaf 19 is removed by raising the 45 springs 22 and said binder leaf is moved to the left to the position shown in Fig. V. The arched rods 29, 30 are raised to vertical positions and the swiveled studs 27, 28 are turned to cause said arched rods to assume 50 positions in planes parallel with the transverse medium line of the leaf. In such positions the ends of the arched rods 29, 30 project beyond the right margin of the leaf 19 and the spindles thereof are in vertical 55 positions. The spindles 29^a, 30^a are then inserted in the posts 15, 16. A portion of the

60 sheets 34 may then be raised on the posts 15, 16 and turned back on the arched rods 29, 30 to an inverted position on the binder leaf 19, to the end of exposing the sheet to be removed. The spindles 29^a, 30^a are removed 65 from the posts, the sheet now on the top of the pile may be removed and employed as desired, the remaining sheets being maintained in separate piles by the posts 15, 16 and the arched rods 29, 30. The arched rods 70 29, 30 are again placed in position as continuations of the posts 15, 16 when it is desired to return the separated sheets to the original pile.

When a collocation of sheets 34 is complete 80 and it is desired to bind them permanently the temporary binder leaf 19 is removed from the posts 15, 16 and the leaf 10 is raised to bring the stub 13 over the upper ends of said posts, as suggested in Fig. II. 85 Headed studs 35, one of which is shown in Fig. VI, are then passed through the eyelets 17, 18 and into the upper ends of the posts 15, 16, and said studs may be driven home therein as by blows of a hammer. 90 The ends of the studs 35 are slightly tapered for this purpose. This has the effect of permanently securing and binding the sheets 34 on the posts 15, 16 between the stubs 13, 14. Thereafter the temporary binder leaf 95 19 may be employed with other permanent binder devices during the process of collocating another volume of sheets.

I claim as my invention—

1. A loose leaf binder, comprising permanent binder devices including spaced tubular posts, and a temporary binder leaf adapted to be mounted on said posts and clamped thereto, the temporary binder leaf also provided with arched posts adapted to connect 100 with and form continuations of said tubular posts whereby sheets in the binder may be separated and maintained in separate piles.

2. A loose leaf binder, comprising permanent binder devices including spaced tubular posts, and a temporary binder leaf adapted to be mounted on said posts and clamped thereto, the temporary binder leaf also being provided with pivoted and swiveled arches adapted to be connected with and form continuations of said tubular posts, 110 and clips adapted to hold said arches in inoperative positions.

3. A loose leaf binder, comprising cover leaves flexibly connected, stubs flexibly connected to the inner margins of the cover leaves, spaced tubular posts fixed to one of said stubs, the other stub formed with eyelets registering with said posts, and a temporary binder leaf adapted to be mounted on 120 and clamped to said posts.

4. A loose leaf binder, comprising cover leaves flexibly connected, stubs flexibly connected to the inner margins of said cover leaves, spaced tubular posts fixed to one of 125

said stubs, the other stub formed with eyelets registering with said posts, a temporary binder leaf adapted to be mounted on and adjustably clamped to said posts, and headed studs adapted to be mounted through said eyelets and seated in said posts.

5. A loose leaf binder, comprising cover leaves flexibly connected, stubs flexibly connected to the inner margins of said cover leaves, spaced tubular posts fixed to one of said stubs, the other stub formed with eyelets registering with said posts, a temporary

binder leaf apertured to receive said posts, clamps on said temporary binder leaf, said clamps comprising springs adapted to engage said posts, said springs being cam-operated for releasing them from the posts, and headed studs adapted to be mounted through said eyelets and seated in said posts. 15
